(57) **CLAIM**

The ornamental design for a component analyzer, as shown and described.

DESCRIPTION

FIG. 1 is a front, top and right side perspective view of a component analyzer showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof;

FIG. 8 is a right side elevational view thereof in an opened position; and,

FIG. 9 is a front elevational view thereof in an opened position.

The broken lines in FIG. 9 are included for the purpose of illustrating portions of the component analyzer that form no part of the claimed design.
